UNITED STATES PATENT OFFICE.

ALTON L. GRAY, OF ROCHESTER, NEW YORK, ASSIGNOR TO TODD PROTECTOGRAPH COMPANY, INC., OF ROCHESTER, NEW YORK.

WORK SUPPORT FOR PRINTING APPARATUS.

Application filed July 15, 1922. Serial No. 575,185.

To all whom it may concern:

Be it known that ALTON L. GRAY, a citizen of the United States of America, residing at Rochester, in the county of Monroe 5 and State of New York, has invented certain new and useful Improvements in Work Supports for Printing Apparatus, of which the following is a specification.

This invention relates to work supports, 10 and more particularly to the variety adapted for use with printing apparatus, being in the nature of an improvement on the work table described in Letters Patent No. 1,299,521 issued April 8, 1919, to Todd, Tie- 15 fel and La May, for "checkwriters."

It is desirable to equip printing apparatus of a character described in said Letters Patent with a work table for supporting the work during its feeding movement 20 through the machine, and to movably support the table, pivotally or otherwise, on the machine so that it may be moved to a folded, out-of-the-way position when the machine is not in use, to occupy less space, protect 25 the table against injury, facilitate the application of a dust cover to the machine. It is also desirable to provide such a table with an extensible gauge-bar for initially locating the work relative to the machine. Most 30 of the work printed on such a machine, as for example, a supply of checks, is of a uniform size, to which the gauge-bar is adjusted by measurement, and it has been found desirable to provide stop means for 35 limiting movement of the gauge-bar at a customary position of adjustment while otherwise permitting adjustment of the bar to suit work of a different size and also movement of the bar to the folded position 40 referred to. One object of the invention, therefore, is to provide a simple and practical stop means, conveniently adjustable to limit the movement of the gauge-bar in a predetermined position, so that the bar may 45 be quickly returned to such position after temporary adjustment to suit other work or after having been folded with the table, without remeasurement of the customary work.

To these and other ends the invention consists in certain improvements and combinations of parts all as will be hereinafter more fully described, the novel features being pointed out in the claims at the end of the 55 specification.

In the drawings:

Fig. 1 is a top view of the work table, partly broken away.

Fig. 2 is an end view of part of the table, with a section broken away to show the means of securing the gauge-bar thereto.

Fig. 3 is the same as Fig. 2 with more of the parts broken away to show the detail, and with one of the parts in a different position.

Fig. 4 is a section through the line 4—4 of Fig. 1.

The work support or table consists of a plate 1 having a downturned marginal portion 2 formed to extend along the entire length of one side, as shown in Fig. 1 and in dotted outline in Fig. 4, the opposite side of the table being provided adjacent its inner end with a smaller downturned portion 3. Each of these depending portions is provided with an opening to receive a stationary rod 4 carried by the machine casing, the table being slidably supported by this rod and by brackets 5 slidably secured to a similar rod 6 directly below and parallel with rod 4, both rods extending along the side of the machine casing and being fastened to the latter at either end, as by means of brackets 6a. The plate 1 is also provided, on the same side as the portion 3, with another downturned portion 7, having a slot 8, a similar slot 88 (see Fig. 1) being provided in the portion 2 directly opposite slot 8. A rod 9 connects the brackets 5 and is free to move in the slots 8 and 88. The brackets 5 are also connected by a brace rod 10. In the action of folding the table or shelf against the machine the plate 1 pivots on the rod 4 and the brackets 5 pivot on the rod 6, the slots 8 and 88 taking care of the motion of the other end of the brackets relative to the table.

The plate 1 has a small upturned ear 11 which, together with an aligned, unturned flange 12, serves as a guide for one edge of the check as it advances into the machine. There is also provided an end gauge for gauging the degree to which the check is projected into the machine to receive the first impression at the left-hand end thereof, and whereby the exact distance of the beginning of the writing from that end may be determined. This gauge consists of a bar 13 provided with an upturned end flange 14 and a longitudinal slot 15, and is secured to

the under side of the plate 1 by means of a stud 16 fixed in the plate and extending through slot 15. The gauge-bar is thus slideable longitudinally toward and from the machine, being held in frictional engagement with the table by a compression spring 16^a, Fig. 2, coiled about the stud between a keeper 16^b on the outer end thereof and a washer 16^c bearing against the gauge-bar.

10 Four small indentations 17 in the plate 1 serve, in connection with the edges of the slot 15, to maintain the gauge-bar parallel with the line of feed of the check. This gauge-bar is also provided with a scale 17^a

15 along one edge of the slot 15, thus affording a means of marking the extent to which the flange 14 has been pulled out from the edge of plate 1.

The invention comprises the provision of 20 adjustable stop means for limiting the sliding movement of the gauge-bar to mark a customary, predetermined position to which it may be conveniently returned without remeasurement of the customary check. To 25 this end one edge of the gauge-bar is provided with teeth to form a rack 18 (Fig. 1), for engagement with the teeth of a pinion 19 rotatably secured to the underside of the 30 plate 1. This pinion is provided with a stop portion or tooth 20 wider than the rest of the teeth, and is supported in such a way that it may be lifted away from the plate 1 and thus out of engagement with the rack 18, for rotarily adjusting the position 35 of the stop portion 20 relative to the rack of bar 13. Thus a knob 21 provided with a knurled shoulder 22 is secured to the pinion and countersunk to receive a compression spring 23 surrounding a stud 24 on which 40 the pinion is rotatably carried. The stud 24 is secured at one end to the plate 1, Figs. 3 and 4, and is tapped at its other end to receive a screw 25, a washer 26 being provided between the stud and the screw head to hold 45 one end of the spring 23, the other end of which engages a shoulder on the knob to yieldably hold the latter and a pinion against the table and in co-operation with the rack 18. By grasping the knob 21 the 50 pinion may be lifted out of engagement with the teeth of rack 18 against the tension of the spring 23, turned to bring its stop portion 20 to any desired position relative to the rack, and then reengaged with the latter. 55 When the bar is moved in or out the pinion is rotated until stop portion 20 engages the rack and stops further movement in the same direction.

In operation, when it is desired to adjust 60 the device to stop the gauge-bar in a given position the pinion 19 is lifted away from plate 1 by means of knob 21 and thus out of engagement with the rack 18, as shown in Fig. 2. The gauge-bar 13 is then moved 65 to the desired position, corresponding, for

example, to a customary size of check. The pinion is now allowed to fall back into position against the plate 1 and into mesh with the rack in such a relation that the portion or tooth 20 will be adjacent the teeth of rack 70 18, to prevent further outward movement of the latter. It will be seen that with the tooth 20 in this position any attempt to move the gauge-bar 13 outward will cause the tooth 20 to be brought to bear against the 75 teeth of the rack 18, and thus prevent any further outward movement of the gauge-bar. The gauge-bar may then be pushed in to any other position, or to facilitate folding of the table. It is then only necessary 80 in subsequent use of the gauge to pull it out until its movement is arrested by the action of the tooth 20 to restore it to the position at which it has previously been set.

The stop may be adjusted in the manner 35 described, of course, to similarly limit inward movement of the gauge-bar, although its use is ordinarily as above described. As apparent from the above description and the drawings, the device is simple and inexpensive in construction, and convenient and effective in operation.

What is claimed is:

1. A work support for printing apparatus comprising a gauge adjustable to different 95 positions on the support to suit the work and provided with gear teeth, a toothed wheel rotatable on the support with its teeth in mesh with those of said gauge, and a device for variably limiting the rotation of said 100 wheel and thereby stopping the movement of said gauge in different positions of adjustment.

2. A work support for printing apparatus comprising a gauge movable in opposite directions on the support to different positions, and provided with gear teeth, and a toothed wheel rotatable on the table in mesh with the gauge teeth and provided with stop 105 means for limiting its rotation and the 110 movement of the gauge.

3. A work support for printing apparatus comprising a gauge bar adjustably slideable on the table and provided with a toothed portion, a toothed wheel rotatable on the 115 table in mesh with said bar and also movable axially into and out of meshing relation therewith, and stop means on said wheel for limiting rotation thereof and stopping said bar in a selected position determined 120 by the rotary adjustment of the wheel while out of mesh with said bar.

4. In a printing apparatus, a work table, means pivotally supporting the same for folding movement to an out-of-the-way position, a gauge-bar slideable on the table for adjustment to suit the work, and for movement to retracted position when the table is folded, a rack on said gauge-bar parallel with the direction of movement thereof, a 125

stud on said table, a pinion having a rotary engagement with the rack to limit the outward movement of the bar in a position determined by the rotary adjustment of the 10 pinion while out of mesh with the rack.

5 rack, means normally maintaining the pinion in mesh with the rack, and an untoothed peripheral portion on the pinion for

In testimony whereof I affix my signature.

ALTON L. GRAY.
